UNITED STATES PATENT OFFICE.

HERBERT A. ZIEGENHAGEN, OF LESUEUR CENTER, MINNESOTA.

PLOW LEVER.

Application filed October 8, 1921. Serial No. 506,439.

To all whom it may concern:

Be it known that I, HERBERT A. ZIEGENHAGEN, a citizen of the United States, residing at Lesueur Center, in the county of 5 Le Sueur and State of Minnesota, have invented a new and useful Plow Lever, of which the following is a specification.

This invention aims to provide simple means whereby a lever, carrying a latch 10 adapted to cooperate with a segment, may be operated from a remote point, the structure being of peculiar utility in operating plow levers from the tractor which draws the plow.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, 25 within the scope of what is claimed, changes in the precise embodiment of the invention shown can be made without departing from the spirit of the invention.

In the accompanying drawings:—

30 Figure 1 shows in side elevation, a device constructed in accordance with the invention; Figure 2 is a top plan wherein parts are broken away; Figure 3 is a section taken on the line 3—3 of Figure 2, parts remaining 35 in elevation; Figure 4 is a fragmental detail showing the connection between said parts in Figure 3; Figure 5 is a fragmental elevation depicting the opposite side of the lever and segment from that shown in Figure 1; Figure 6 is a fragmental longitudinal section showing a portion of the actuating shaft; Figure 7 is a section on the line 7—7 40 of Figure 2.

The numeral 1 denotes a segment whereon 45 a lever 2 is fulcrumed, the lever being adapted, as indicated at 62, for connection with the part which the lever operates, the lever being fulcrumed at 3 on the segment, the fulcrum element being in the form of a bolt, 50 if desired. An offset tongue 4 is secured at 5 to one side of the lever 2 and overlaps the curved portion of the segment 1. The tongue 4 and the lever 2 are supplied with alined slots 6. A tubular guide 7 is secured 55 to that side of the lever 2 which is remote from the tongue 4. A latch 8 is mounted

for right line sliding movement in the guide 7 and includes a transverse finger 9 movable in the slots 6 and adapted to cooperate with the teeth 10 of the segment 1, under the 60 action of a retractile spring 11 connected by attaching elements 12 to the finger 9 and to the fulcrum bolt 3.

A shaft 14 which may be in the form of a bolt, is mounted in the upper end of the 65 lever 2. A clutch member 15 surrounds the shaft 14 and is fixed on the upper end of the lever 2. A movable clutch member 16 is journaled on the shaft 14 and has a recess 17 defining a flange 18, the flange 18 and the 70 fixed clutch member 15 being supplied with interengaging radial teeth 19. A compression spring 20 surrounds a portion of the shaft 14 and abuts at one end against the movable clutch member 16, the spring abutting 75 at its other end against a nut 21 on the shaft, the shaft having a head 22 engaging the lever 2. The spring 20 serves to maintain the teeth 19 of the clutch members 16 and 15 detachably interengaged. The clutch 80 member 16 includes a tubular bearing 23 disposed approximately at right angles to the axis of the shaft 14.

The device includes a longitudinally extensible actuating shaft, which is a composite structure, the shaft including a member 24 journaled in the bearing 23 and having a squared portion 25. A nut 26 is threaded on the member 24 and cooperates with one 90 end of the bearing 23. The part 24 has an end 27 which is squared as at 28 and threaded as at 29. A crank arm 30 is held on the squared portion 28 of the member 24 by a nut 31 threaded on the part 29 of the member 24. The crank arm 30 includes an extension 32 disposed parallel to the shaft member 24 and parallel to the bearing 23, the extension 32 having a depending ear 33 which is outwardly offset as shown at 34. A pivot element 35, such as a bolt, is carried 100 by the ear 33 and is disposed co-axially with the shaft 14, the pivot element carrying superposed nuts 36. A link 37 extends longitudinally of the lever 2 and is supplied at one end with a hook 38 engaged with the 105 latch 8. At its opposite end, the link 37 is supplied with an enlarged eye 39, loosely mounted on the pivot element 35 and located between the ear 33 and the superposed nuts 36 on the pivot element.

The numeral 40 denotes a socket constituting a part of the actuating shaft herein-

before mentioned. The squared portion 25 of the member 24 of the actuating shaft is held against rotation in the socket 40, but is longitudinally slideable therein. At its 5 outer end, the socket 40 terminates in a loop-shaped handle 41. There are seats 42 in the squared portion 25 of the member 24, and in any of the seats 42, the transverse end 43 of a latch 44 may be received, the latch being 10 pivoted at 45 on wings 46 carried by the socket 40. A compressing spring 47 is interposed between the latch 44 and the socket 40 and tends to maintain the end 43 of the latch engaged with any one of the seats 42 15 in the member 25. The latch 44 is pivoted at 48 to one arm of a bell crank lever 49 fulcrumed at 50 on a standard 51 carried by the socket 40. The numeral 52 marks an operating rod, pivoted at its inner end, as shown 20 at 53, to the bell crank lever 49, the operating rod being slideable in a guide 54 on the socket 40 and carrying a transverse grip 55 disposed parallel to the handle 41 on the socket 40.

25 By means of the handle 41, rotation may be imparted to the actuating shaft including the socket 40 and the shaft member 25, the portion 24 of the said shaft member rotating in the bearing 23. From the member 24, a swinging movement is imparted 30 to the crank arm 30, the extension 32 thereof, and the link 37 withdrawing the latch 8 out of engagement with the teeth 10 of the segment 1, the spring 11 being extended. 35 After the latch has been disengaged from the teeth 10 of the segment 1, the lever 2 may be swung on its fulcrum 3, through the instrumentality of the actuating shaft 25-40. When the lever 25 has assumed an 40 adjusted position, the handle 41 may be released, whereupon the finger 9 of the latch 8 will cooperate with and engage the teeth 10 of the segment 1, under the action of the spring 11, the part 24 rotating in the bearing 23 to permit such an operation.

45 The actuating shaft 25-40 may be disposed at any angle with respect to the lever 2, by simply swinging the said actuating shaft on its pivotal mounting, represented 50 by the shaft 14, the spring 20 yielding to permit a shifting of the clutch member 16 with respect to the clutch member 15, the teeth 19 serving to hold the actuating shaft 40-25 in any position to which it may have 55 been adjusted, angularly with respect to the lever 2.

60 The handle 41 on the actuating shaft 40-25, and the transverse grip 55 on the operating rod 52 may be grasped simultaneously, the operating rod being drawn out-

wardly, the bell crank 49 being tilted, the spring 49 being compressed, the latch 44 being tilted on its fulcrum 45, and the part 43 of the latch being withdrawn from any one of the seats 42 wherewith it may happen 65 to have been engaged. Then, the socket 40 may be slid inwardly or outwardly on the member 25, thereby varying the effective length of the actuating shaft, and when the actuating shaft has been adjusted to a desired length, the part 43 of the latch 44 may be engaged with any one of the seats 42 70 simply by releasing the transverse grip 55 and permitting the parts to respond to the action of the spring 47. 75

What is claimed is:—

1. In a device of the class described, a lever fulcrumed for swinging movement, a latch carried by said lever, an actuating shaft disposed at an angle to the lever and comprising slidably connected parts which are relatively movable to vary the length of the shaft, means for holding said parts in adjusted position with respect to each other, and means for connecting the shaft with the 85 latch.

2. In a device of the class described, a lever fulcrumed for swinging movement; a latch carried by the lever; an actuating shaft disposed at an angle to the lever and comprising slidably connected parts which are relatively movable to change the length of the shaft; means for holding said parts of the shaft in adjusted positions with respect to each other; means for mounting one of 90 said parts for rotation on the lever; and means for connecting said part of the shaft with the latch.

3. In a device of the class described, a lever fulcrumed for swinging movement; a 100 latch carried by the lever; an actuating shaft disposed at an angle to the lever and comprising relatively movable parts effective to change the length of the shaft; means for holding said parts in adjusted positions with respect to each other; means for mounting one of said parts of the shaft for rotation on the lever; means for mounting said part of the shaft adjustably on the lever to vary the angle between the shaft and the lever; and means for connecting said part of the 105 shaft with the latch. 110

In testimony that I claim the foregoing as my own, I have hereunto affixed my signature in the presence of two witnesses.

HERBERT A. ZIEGENHAGEN.
